UNITED STATES PATENT OFFICE.

CHARLES E. WAREAM, OF CINCINNATI, OHIO, ASSIGNOR TO THE AMERICAN LAUNDRY MACHINERY COMPANY, OF NORWOOD, OHIO, A CORPORATION OF OHIO.

GARMENT PRESS.

Application filed October 15, 1921. Serial No. 507,984.

This invention relates to improvements in garment presses.

The objects of this invention are to provide an improved garment press in which 5 the lower buck or pressing member is raised and lowered into and out of pressing engagement with the upper pressing member, together with means also for moving the lower buck laterally into and out of position beneath the upper pressing member; to provide means for effecting and controlling the several movements of the lower buck including means for automatically stopping the lower buck upon being moved laterally 15 from under the upper pressing member; further, to provide a steam valve mechanism for effecting the raising and lowering of the lower buck and an electric control means for the steam valve mechanism; to 20 provide also an improved finger guard with means for automatically moving the same into and out of operative position according to the position of the lower buck; and also to provide an improved structure of 25 supporting and operating means for permitting the several movements of the lower buck.

Other objects will appear from the following description and claims when considered together with the accompanying drawings.

Fig. 1 is a front elevation of my improved garment press; Fig. 2 is a rear elevation of the same; Fig. 3 is a vertical section taken on line 3—3 of Figs. 1 and 2; Fig. 4 is a vertical section taken on line 4—4 of Figs. 1, 2 and 7; Figs. 5 and 6 are detail views, partly in section, of one of the third rails; Fig. 7 is a horizontal section on line 7—7 of Figs. 1, 2 and 3; Fig. 8 is a vertical longitudinal section showing in detail the operating mechanism on line 8—8 of Figs. 7, 9 and 10; Fig. 9 is a vertical transverse section showing in detail 35 the operating mechanism taken on line 9—9 of Figs. 1, 7 and 8; Fig. 10 is a vertical section taken on line 10—10 of Figs. 1, 2 and 7; Fig. 11 is a detail view showing the clutch operating mechanism; Fig. 12 is a transverse section of the timing gear taken 40 on line 12—12 of Figs. 7, 9 and 10, certain cams being omitted for simplicity of illustration, and Fig. 13 is a diagram of the electric control system.

The base 1 is provided with the support-

ing arms 2 from which extend upwardly the standards 3 for supporting the upper pressing member 4 by means of the arms 5 extending inwardly from the standards 3. The upper pressing member 4 is a hollow 60 body, as shown in the drawings, and is adapted to be heated by steam in any suitable and well known manner as is already old in the art. This upper pressing member remains stationary at all times. The 65 lower pressing member 6, which has a layer of padding 7, is supported by the pedestal 8 which in turn is carried by the carriage 9. The tray 10 is also provided. The carriage 9 is adapted to be raised and lowered 70 for bringing the lower pressing member or buck into operative engagement with the upper pressing member and is also adapted to be moved laterally so as to move the lower pressing member into and out of position 75 beneath the upper pressing member. The press, therefore, is adapted for operation, as will appear, by two stages, to wit, a first stage in which the lower pressing member is moved horizontally into registering relation with the upper pressing member and then vertically into pressing relation or engagement therewith, and a second stage in which the lower pressing member is lowered 80 away from the upper pressing member and then moved out of registering relation therewith. The pedestal 8 is provided with a depending post 11, which is adapted to be engaged by the plunger rod 12 actuated by the plunger 13 in the cylinder 14. Steam 85 is adapted to enter through the inlet 15 through the inlet valve indicated at 16 to the underside of the plunger 13 for raising the plunger rod 12 against the depending post 11 so as to raise the lower pressing 90 member into its upper engaging position. The outlet valve is indicated at 17. The valve arrangement may be designed after that shown in my co-pending application Serial No. 348,874, filed Jan. 12, 1920. Then 95 upon shutting off the inlet valve connection 16 and opening the outlet valve 17 so as to permit the steam to escape through the outlet 18, the lower pressing member is permitted to descend to its lower or inoperative position. The valve 16 has the valve stem 19, which is connected to link 19 which in turn is pivotally connected at 20 to the one end of the rocker arm 21 pivotally mounted at 22 upon the bracket 23 on the 100 105 110

frame of the machine. The outlet valve 17 has its stem 24 connected to the link 25 which in turn is pivotally connected at 26 to the other end of the rocker arm 21. The 5 arm 27 is connected at its one end to the axis of the crank arm 23 and has pivotal connection at its other end at 28 to the operating rod 29, which, when operated in the manner to be later described, will effect 10 operation of the valve mechanism in the manner just now referred to. The pedestal 8 is provided with the depending posts 30, which are adapted to have guiding engagement with recesses in the correspondingly 15 formed wells or sockets 31 provided with the springs 31^a to cushion the lowering movement of the lower pressing member.

The carriage 9 is provided with the depending bracket arms 32 provided with lateral flanges 33 for sliding engagement with rollers 37 on the third rail member 34, which is mounted in the upwardly extending brackets 35 on the frame of the machine. These brackets are provided also with overhanging 25 housing portions 36. The third rails 34 carry also the rollers 38 for engagement between the edges of the flanges 33 and the inwardly extending portions or tracks 39 on the brackets 35. The brackets 35 are provided also with the tracks 40 and 41 for engagement by the rollers 37. The carriage 9 is provided also with a bracket 45 through which extends the pin 46 surrounded by the springs 47 on the two sides of the bracket. 30 The free end of the pin 46 carries the nut 48 as an abutment for one of the springs. The other end of the rod 46 has pivotal connection at 49 with the lever arm 50, which in turn is pivotally mounted at 51 upon a 35 bracket portion of the machine frame. The lever arm 50 is provided with a depending arm 52, the lower end of which has swivel connection at 53 with the link arm 54, which is in turn swivelly connected at 55 with one 40 end of the crank 56, the other end of which is fixed upon the shaft 57 for operation of the mechanism just now described. A suitable housing is provided for the operating mechanism. By operation of the crank arm 56 it will be seen that the lower buck is 45 moved laterally into and out of position beneath the upper pressing member. The means for operating the crank arm 56 will be described later.

55 The electric motor 58 drives the worm 59, which meshes with the worm gear 60 carried by a sleeve 61 loosely mounted upon the shaft 57. The same sleeve 61 carries also the pinion 62 and the clutch disc 63. The clutch 60 disc 63 is provided on its one side with the teeth 64, which are adapted for clutching engagement with the corresponding teeth 65 on the clutch 66, which is keyed to the shaft 57. The clutch 66 is normally forced by the 65 spring 67 toward clutching engagement with

the teeth 64 and is held in unclutched or released position by means of the yoke member 68 pivotally mounted upon the frame at 69. This yoke member has swivel connection at 70 with the clutch 66 and carries a 70 roller 71 for actuation by the cam member 72 provided upon the clutch plate 63. While the cam member 72 engages the roller 71, the clutch will be held in disengagement, which means that the carriage 9 will remain 75 stationary. But upon rotation of the clutch disc 63 so as to discontinue the engagement between the cam 72 and the roller 71, the spring 67 will cause engagement of the teeth 64 and 65 with the result that the shaft 57 80 will be rotated and will cause lateral movement of the carriage through the connections above described.

The pinion 62 meshes with the timing gear 73 which is pivotally mounted in the frame 85 of the machine. Upon one face of this timing gear 73 there is provided cam member 74 while the other face of the timing gear carries the cam member 75, these two cam members being adapted to engage in proper sequence the rollers 76 carried by the arms of the yoke member 77, which is pivoted at 78 in the frame of the machine. The lower end of the yoke member 77 has pivotal connection at 79 with the link 80 whose other end is pivotally connected at 81 with the depending arm 82 which in turn has fixed connection with the longer arm 84. The two arms 82 and 84 are pivotally mounted at 83 on the bracket 85 provided on the frame 100 of the machine. The lower end of the arm 84 is pivoted at 86 to the sleeve 87 which is movably mounted upon the rod 29 between the springs 88, which are provided with suitable abutments 89 upon the rod 105 29. Thus it will be seen that upon operation of the electric motor, the pinion 62 will drive the timing gear 73, which will cause proper timed engagement of the cam members 74 and 75 with the rollers 76 for operation 110 of the connecting rod 29. In this way the steam valve mechanism is actuated so that the steam is permitted to force the lower pressing member into engagement with the upper presssing member, and then when 115 desired by the operator, the steam can be released so as to permit the lower pressing member to descend.

The timing gear 73 carries also contact segments 90, 91 and contact ring 92 for controlling the circuits through the electric motor so as to automatically cut out the motor at predetermined points in the raising and lowering of the lower pressing member. Contact plates 93 and 94 are also provided for electric connection between the contact ring 92 and the contact segments 90 and 91. The brushes 95 and 96 are adapted for circuit closing engagement with the contact segments and the contact ring 130

respectively. Contact segments 90 and 91 are separated by gaps 97 and 98 which represent the points at which the motor will be automatically stopped.

- 5 Referring to the diagram of the electric control system for the motor, the safety switch 99 is normally closed at all times but can be opened to stop the motor at any time desired. When switch 99 is closed and
- 10 when the parts are in the position shown in the electric diagram, there will be a closed circuit from the positive side of the main line through the switch 99, wire 100, brush 96, contact ring 92, plate 94, contact seg-
- 15 ment 91, brush 95, wire 103 and through the motor to the negative side of the main line. The motor under these conditions will be in operation and will cause rotation of the timing gear for actuation of
- 20 the parts controlled thereby. Then, with the parts in the position shown in the drawings, cam 75 will actuate yoke member 77 so as to open the steam inlet valve and raise the lower pressing member to
- 25 pressing position. When, however, the timing gear has rotated to the position where brush 95 is opposite the gap 97, the circuit through the motor will be broken and the motor will therefore stop. The steam pres-
- 30 sure will however remain and the lower pressing member will remain in engagement with the upper pressing member until the motor is again started for lowering the same. When, in the judgment of the operator,
- 35 the pressing has been completed, he will close spring release switch 104 so as to close the circuit from the positive side of the main line through wire 105, switch 104 and through the motor to the negative side of
- 40 the main line. The operator will hold switch 104 closed only so long as is necessary to operate the motor sufficiently to cause movement of the timing gear to effect electric contact between the other contact seg-
- 45 ment and brush 95. Then upon releasing switch 104 the following circuit is established through the motor: from the positive side of the main line, through switch 99, wire 100, brush 96, contact ring 92, connecting plate 93, segmental contact 90, brush 95, wire 103 and through the motor to the nega-
- 50 tive side of the main line. Such operation of the motor and timing gear 73 will cause the roller 76 on the other side of the timing gear to be actuated by the cam member 74 with the result that the connecting rod 29 is then moved in the opposite direction so as to reverse the steam valve connection by closing off the inlet valve and opening the outlet valve, to thereby permit the lowering of the lower pressing member to idle position. This condition of the steam valves is maintained until the lower pressing member has not only been lowered but also until
- 55 the carriage is moved outwardly and the
- lower buck brought to a position from under the upper pressing member as before explained. Reference to the drawings will show that by the time the timing gear has caused the lowering of the lower pressing member, dis-engagement will be effected between the cam 72 and the roller 71 so as to permit the clutch 66 to be thrown into operation for rotation of the shaft 57, which will then cause the lateral movement of the carriage. Then when the carriage has been moved laterally it will be seen that the timing gear 73 has been rotated to such position as to cause the gap 98 to come opposite the brush 95 and to break the circuit through the motor. The lower pressing member is then in proper position for removing the work which has been operated upon and to place another garment upon the same for pressing operation. When this has been done the operator will close the switch 104 and hold the same closed until the motor is permitted to run sufficiently long to cause the timing gear 73 to bring the segmental contact 91 opposite the brush 95. It will be noted that the clutch 66 is still in operative engagement, and that upon operation of the motor as just described, the carriage will be moved back again so as to place the lower pressing member in a position beneath the upper pressing member. As soon as this has been accomplished, the cam 72 will have been moved out of engagement with the roller 71 so that the clutch 66 becomes disengaged and the shaft 57 is no longer rotated. The lower pressing member is then caused to be moved upwardly in the manner as already described in the first part of the recital of operations.
- I have provided also a finger guard 106 carried by the arm 107, which is pivotally mounted at 108 on the top of the upper pressing member 4. The rear end of the arm 107 has pivotal connection at 109 with the downwardly extending rod 110, the lower end of which is pivoted to one arm of the bell crank lever 111. This bell crank lever is pivotally mounted at 112 upon the frame of the machine and is adapted to be engaged at its free end portion by a roller 113 carried by an arm 114 depending from the flange 33 of the carriage. These parts are so constructed and arranged that when the lower buck is positioned beneath the upper pressing member, the finger guard 106 is lowered so as to prevent accidental insertion of the operator's fingers between the two pressing members. This operation is effected by engagement of the roller 113 with the bell crank lever 111, which is thereby caused to rock and to effect the raising and lowering movement of the finger guard through the connections described. When, however, the lower buck occupies a position out from under the upper pressing

member, the finger guard is caused to occupy a raised position so as to permit ready access to the press. A cushion spring 115 is provided for the one end of the bell crank lever 111 and a set screw 116 is provided also for engagement with the frame work of the machine structure.

What I claim is:

1. A garment press including relatively movable pressing members, a carriage supporting one of said members and movable laterally with said pressing member, said one pressing member being movable towards and from pressing engagement with the other pressing member, fluid means for effecting said pressing engagement between said members, and electric means for effecting lateral movement of said carriage and for controlling said fluid means.
2. A garment press including relatively movable pressing members, a carriage supporting one of said members and movable laterally with said pressing member, said one pressing member being movable towards and from pressing engagement with the other pressing member, fluid means for effecting said pressing engagement between said members, means for effecting lateral movement of said carriage, and cam means actuated by said last named means for controlling said fluid means.
3. A garment press including relatively movable pressing members, a carriage supporting one of said members and movable

laterally with said pressing member, said one pressing member being movable towards and from pressing engagement with the other pressing member, an electric motor for moving said carriage laterally, means controlled by said electric motor for moving said one pressing member towards and from the other pressing member, and means for automatically breaking the circuit through said motor at predetermined points in the operation of the press.

4. A pressing machine, comprising a stationary pressing head, a carriage slideable laterally from a position at one side of the same into and out of registering relation beneath the same, a pressing bed supported by said carriage for cooperation with said head, power operating and controlling means for said bed operable in two stages, one stage of said operation moving the carriage laterally into position beneath the head and the bed and upwardly into pressing engagement therewith, and another stage moving the bed downwardly out of pressing engagement with the head and the carriage laterally out of registration therewith, said operating and controlling means including an electric motor, a commutator controller therefor, and means for closing the circuit to said motor independently of said controller.

In testimony whereof I hereby affix my signature.

CHARLES E. WAREAM.
